(57) **CLAIM**

The ornamental design for a portable external defibrillator, as shown and described.

DESCRIPTION

FIG. 1 is a top front perspective view of a portable external defibrillator showing our new design;

FIG. 2 is a front elevational view thereof;

FIG. 3 is a back elevational view thereof;

FIG. 4 is a right side elevational view thereof;

FIG. 5 is a left side elevational view thereof;

FIG. 6 is a top plan view thereof;

FIG. 7 is a bottom plan view thereof;

FIG. 8 is a top front perspective view of the portable external defibrillator showing our new design, with the door in open position;

FIG. 9 is a front elevational view thereof;

FIG. 10 is a back elevational view thereof;

FIG. 11 is a right side elevational view thereof;

FIG. 12 is a left side elevational view thereof;

FIG. 13 is a top plan view thereof; and,

FIG. 14 is a bottom plan view thereof.

The broken line showing in FIGS. 8, 9 and 13 is for illustrative purposes only and forms no part of the claimed design.
